(57) **CLAIM**

The ornamental design for a particulate filter for diesel engine, as shown and described.

DESCRIPTION

FIG. 1 is a front view of a particulate filter for diesel engine showing our new design;

FIG. 2 is a top plan view thereof;

FIG. 3 is an enlarged right side view thereof;

FIG. 4 is an enlarged left side view thereof;

FIG. 5 is an enlarged cross-sectional view taken along line 5—5 in FIG. 1;

FIG. 6 is an enlarged cross-sectional view taken along line 6—6 in FIG. 1; and,

FIG. 7 is an enlarged cross-sectional view taken along line 7—7 in FIG. 3.

The rear view is omitted since it is identical with the front view. The bottom plan view is omitted since it is identical with the top plan view.
